United States Patent Office.

ISAIAH A. CLIPPINGER, OF NEWTON, IOWA.

Letters Patent No. 96,887, dated November 16, 1869; antedated November 8, 1869.

IMPROVEMENT IN CARRIAGES.

The Schedule referred to in these Letters Patent and making part of the same.

To all whom it may concern:

Be it known that I, ISAIAH A. CLIPPINGER, of Newton, in the county of Jasper, and State of Iowa, have invented certain new and useful Improvements in Carriages and similar vehicles; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to carriages and similar vehicles, and consists in the novel construction and arrangement of a wrought-iron bolt, to prevent lateral and longitudinal strain upon the springs, as hereinafter explained.

In the drawings—

Figure 1 represents a side view, and

Figure 2, an end view of my device as attached and arranged.

As is well known, in the ordinary construction of carriages, the springs form the connection between the body and the axle-trees, and are attached to them with bolts, for the purpose of keeping them in position.

In using the carriage with the springs attached in this way, and without any other support, there is more or less lateral and longitudinal strain on the fastenings, which sometimes work loose, when the springs are liable to injury.

The object of my invention is to furnish the spring with a support, that will relieve the fastenings from these strains.

To accomplish this, I make a wrought-iron bolt, A, of suitable length, strength, and form for the purpose, and with its upper end flattened and bent at right an-

gles to its length. This bolt A, I employ to relieve the front spring B of a carriage from lateral and longitudinal strain, by attaching its upper end to the upper side of the spring, and inserting its lower end loosely in an eye of the head C of the reach, so as to be in a vertical position, as clearly shown in both figures.

I make the head C of the reach out of cast-iron, and in form as shown in fig. 1, and connect it to the head-block D, by means of a tenon having ears, through which I pass bolts E. The outer end of this head, I mortise, and tenon the end of the reach, so as to connect the body and head of the reach, as shown by the dotted lines in fig. 1, and then iron them on the sides, so as to connect them together as well as to the head-block.

The same bolts that are used to connect the head of the reach to the head-block, I also use to connect the side-irons to them.

In this way, by the use of a simple wrought-iron bolt, and a cast-iron or other suitable head for the reach, I am able to provide a cheap and effective device for removing the lateral and longitudinal strain from the spring, thus protecting it from many injuries to which it would otherwise be liable, and consequently increasing its durability and usefulness.

Having thus described my invention,

What I claim, is—

The wrought-iron bolt A, in combination with the reach-head C, constructed and arranged substantially as herein described, for the purpose of protecting the spring against lateral and longitudinal strain, as set forth.

I. A. CLIPPINGER.
